Ernest Hopkins

UNITED STATES PATENT OFFICE.

THOMAS B. HUESTIS, OF BRISTOL, RHODE ISLAND, ASSIGNOR TO NATIONAL INDIA RUBBER COMPANY, A CORPORATION OF RHODE ISLAND.

CIRCULAR-FEED ATTACHMENT.

Application filed February 26, 1921. Serial No. 447,944.

To all whom it may concern:

Be it known that I, THOMAS B. HUESTIS, a citizen of the United States, residing at Bristol, in the county of Bristol and State 5 of Rhode Island, have invented a certain new and useful Circular-Feed Attachment, of which the following is a full, clear, and exact description.

This invention relates to a circular feed 10 attachment, more particularly to an attachment whereby circular or other shaped articles may be automatically fed and stitched with a circular seam on an ordinary sewing machine.

15 In the manufacture of shoes made of canvas or other fabric, particularly those intended for sporting use, or for other purposes where they are subjected to hard usage, it is customary to reinforce the ankle 20 portions of the shoe uppers by securing to them small circular pieces of material, usually of leather, which are known in the trade as "ankle patches." Prior to my invention these patches were sewed on the shoe uppers

25 on an ordinary sewing machine, the operator guiding the shoe upper and superposed patch manually, to form a circular seam around the patch adjacent its periphery. As the operator guides the work by the eye, 30 using the edge of the patch as a gauge, it is evident that considerable skill is required and both hands must be used in order to form a seam which is uniformly spaced inwardly from the edge

35 of the patch, and in the case of an inexperienced or careless operator the seam is more or less irregular, thereby detracting from the appearance of the finished shoe. In either case the speed of operation is con-

40 siderably reduced. In addition, the patch is comparatively small, and in order to guide it during the stitching operation the fingers of the operator are necessarily kept quite close to the stitch-forming mechanism,

45 involving considerable risk of injury. An object of my invention is to provide an improved means for feeding work, to be operated upon, in a circular path past the point of operation.

50 Another object is to provide a circular feed attachment for sewing machines.

Still another object is to provide an attachment for converting the usual straight line feed of a sewing machine into a circular 55 feed.

A further object is to provide an improved means for automatically sewing a circular seam.

A still further object is to provide a gauge for properly locating the work. 60

A still further object is to increase the speed, accuracy, and safety of operation when sewing a circular seam.

For a detailed disclosure of the invention reference is had to the accompanying specification and drawings, in which: 65

Fig. 1 is an elevation of the stitch-forming mechanism of a sewing machine with my invention attached;

Fig. 2 is a part elevation and part vertical section of Fig. 1; 70

Fig. 3 is an elevation showing the presser foot of the machine raised and with the upper member of the work clamp partly thrown back;

Fig. 4 is a plan of Fig. 3 with the presser bar shown in section.

Referring to the drawings, the numeral 1 represents the work bed of a sewing machine, above which is disposed a needle bar 2 carrying needles 3, and a presser bar 4 having a presser foot 5, below which latter is disposed the feed dog 6, all of said parts being of any usual or desired construction. 80

A collar or sleeve 7 is rigidly secured to the presser bar above the presser foot and is provided with an upwardly projecting extension 8 through which is secured a stop screw 9. Loosely mounted on the presser bar is a second sleeve 10 having a horizontal slot 11 therein, the lower wall of which is formed with a recess 12, and by reference to Fig. 3 it will be seen that the stop screw 9 projects into the slot 11 and limits the 85

rotary movement of sleeve 10 on the presser bar. A coil spring 13 is disposed on the presser bar between the sleeves 7 and 10, and tends to urge the sleeve 10 in an upward direction. Hence, when the sleeve is so disposed that the recess 12 is in line with the 90

stop screw 9, the spring urges the sleeve 10 upwardly to yieldingly hold it in position. An arm 14 extends outwardly from the sleeve 10 and is provided at its free end with a downwardly projecting bearing sleeve 15, the lower end of which carries a gauge and guard 16, which latter is cut away at one side, as shown at 17. The shank 18 of one member 19 of a work clamp is rotatably and 95

slidably mounted in the sleeve 15 with its 100

105

110

upper end projecting slightly above the arm 14. The shank 18 and clamp member 19 are yieldingly pressed downwardly by means of a spring 20 secured to the arm 14 and bearing at one end against the upper end of the shank 18. In order to limit the downward movement of the shank 18 it is provided with a circular groove 21 adjacent its upper end, in which groove is disposed a U-shaped 5 retaining member 22 the ends of which bear against the top of arm 14. A second work clamping member 23 is rotatably mounted at 24 on a plate 25 secured in the work bed 24 on a plate 25 secured in the work bed of the machine, this second work clamping 15 member being disposed laterally of the feed mechanism of the machine, that is, transversely of the path of movement of the feed dog, as shown in Fig. 4. The clamping member 23 is provided with a series of upwardly projecting teeth 26 adjacent its periphery, and a pin 27 is disposed centrally of the member 23 and adapted to enter a central recess 28 in the lower face of the upper work clamping member 19 when the 20 latter is in operative position.

In operation the presser foot of the machine is raised in the usual manner. Since the upper work clamping member and guard 16 are carried on the presser bar, they will 30 also be raised to the same height as the presser foot. The operator then disposes a shoe upper 29 on the clamping member at the point where it is desired to attach the ankle patch 30 and disposes the ankle patch 35 on top of the upper, using the guard 16 as a gauge to properly center it. The guard 16 is preferably made with a base of the same diameter as the patch to be used, and by moving the patch until it is in alignment with the guard base the guard is thus 40 utilized for centering the patch and properly disposing its edge portion in relation to the needles. The presser foot is then lowered together with the upper clamping member 45 and guard, thereby clamping the work in adjusted position. The pin 27 passes through the work and enters recess 28 to assist the clamping members in holding the work properly centered. It is obvious that 50 the base of the guard 16 need not be necessarily of the same diameter as the patch or other article to be operated upon. It will be seen that the work will be rotatably held by the clamping members at one side of the feed mechanism, which latter is disposed 55 radially of the pivot point 24 and operates in a direction perpendicular to the radius on which it is disposed. Hence, as the stitching proceeds the feed mechanism 60 causes the work to be rotated around the pivot point 24 as a center until the seam is completed. The upper work clamping member 19 and guard 16 are normally yieldably held directly over the lower work

clamping member by the stop screw 9, recess 12, and spring 13, and if for any reason it is desired to obtain access to the work bed of the machine, as, for instance, when changing bobbins, the upper work clamping member and guard are swung rearwardly 70 on the presser bar as far as is necessary, the limit of movement of such parts being fixed by the engagement of the stop screw 9 with the left hand end of the slot 11.

By my invention a circular object can be 75 stitched automatically without any necessity for manual guidance by the operator; the stitching can be accomplished much more rapidly and accurately, and as there is no necessity for the use of the operator's 80 fingers in guiding the work during the operation, all risk to the operator is obviated. The guard 16 not only covers the moving parts of the work clamp during the sewing 85 operation, but also aids in preventing any curling up or misplacement of the shoe upper while being stitched, and, as before stated, forms a gauge to aid in the proper placing of the ankle patch or other article 90 to be sewed.

While a specific embodiment of the invention has been shown and described, it is obvious that numerous changes may be made therein without departing from the spirit of the invention, and it is not limited in its 95 use to the particular operation shown, and may be applied to other machines than sewing machines.

Having thus described my invention, what I claim and desire to protect by Letters Patent is:

1. In a sewing machine, stitch forming mechanism, straight line work feeding mechanism including a presser bar, a rotatable work gripping member movably carried by the presser bar and having a central recess on its under side, a circular rotatable work gripping member coacting therewith and having a roughened portion adjacent its periphery, and a pin disposed centrally of said second member and adapted to enter said recess. 105

2. In a sewing machine, stitch forming mechanism, straight line feed mechanism including a presser bar, a presser foot and a feed dog, a sleeve rotatable on said presser bar, a slot in said sleeve and having a recess in its wall, a stop carried by the presser bar and disposed in said slot, yieldable means tending to urge said recess into engagement with said stop, a rotatable work gripping member carried by said sleeve, and a coacting rotatable work gripping member disposed in transverse alignment with the feed dog. 110

Signed at Bristol, Rhode Island, this 17th day of February, 1921.

THOMAS B. HUESTIS.
